UNITED STATES PATENT OFFICE.

MERRITT L. STODDARD, OF CLEVELAND, OHIO.

WASHING-MACHINE.

SPECIFICATION forming part of Letters Patent No. 723,420, dated March 24, 1903.

Application filed June 25, 1902. Serial No. 113,080. (No model.)

To all whom it may concern:

Be it known that I, MERRITT L. STODDARD, a citizen of the United States, residing at Cleveland, in the county of Cuyahoga, and 5 State of Ohio, have invented certain new and useful Improvements in Washing-Machines; and I do hereby declare the following to be a full, clear, and exact description of the invention, such as will enable others skilled in the 10 art to which it appertains to make and use the same, reference being had to the accompanying drawings, and to the figures of reference marked thereon, which form a part of this specification.

15 This invention relates to washing-machines, and particularly to that class thereof having a rubber oscillating in a semicylindrical or segmental suds-box.

The object of the invention is to improve 20 the construction of the surfaces between which the clothes are rubbed and which effect the cleansing result.

A further object is to generally improve and simplify the construction of such machines, particularly by the provision of an improved removable bottom mat or board in the 25 suds-box.

With these and other objects in view the invention is hereinafter described and claimed, 30 and an embodiment thereof is illustrated in the accompanying drawings, in which—

Figure 1 is a perspective view of the machine. Fig. 2 is a longitudinal vertical section of the rubber and suds-box. Fig. 3 is a 35 plan view of a portion of the washboard or mat removed from the suds-box. Fig. 4 is a bottom plan view of the same. Fig. 5 is a cross-section of one of the slats forming said mat.

40 Referring specifically to the drawings, 6 indicates the semicircular suds-box, supported on legs 6^a. The rubber is indicated at 7 and swings on an axle 7^a, the ends of which enter vertical slots formed in castings 8, secured to 45 the suds-box. This construction is common in the art and permits vertical movement of the rubber to adjust itself to the thickness of clothes underneath.

The wash mat or board, against which the 50 clothes are rubbed, is formed of slats 9, and the rubber 7 is faced with similar slats, fastened to the edges of the side pieces thereof. The mat or stationary board is formed of such slats, joined together by flexible wires 9^a, to

which the slats are stapled, as at 9^b. This lets 55 the mat take the shape of the bottom of the suds-box, from which it is spaced by the thickness of the wires and on which it rests between stops 6^b. The mat is readily removable, as it is not fixed to the suds-box. It can 60 be lifted out to be cleaned or to let the suds-box be cleaned. The working face or front of each slat 9 contains a series of cups or recesses 10, formed therein, forming rough or irregular rubbing-surfaces. Perforations 10^a 65 are formed in the bottoms of the cups to allow the escape of the dirt removed from the clothes through the slats to the lower side or beneath those forming the washboard or mat. This dirt collects and settles between the 70 washboard and the bottom of the box as the water flows in and out through the holes referred to.

The simplicity and cheapness of the machine are obvious. The slats are preferably 75 formed of wood, and the bottom of the suds-box may be formed of wood or metal, preferably the latter. The only other metal parts are the axle and its bearings. The wave-like or back-and-forth motion of the water 80 produced by the swing of the rubber causes a flow of water through the cups and holes which effectively carries the water through the clothes and thoroughly washes them, and as fast as the dirt collects it settles under the 85 board at the bottom of the box, and the water is thereby kept cleaner than would otherwise be the case. The absence of projections on the face of the rubber or washboard avoids tearing or injuring clothes or fine fabrics. 90

What I claim is—

In a washing-machine and in combination a suds-box, a removable washboard therein comprising slats flexibly connected together, each having a series of substantially cup-like recesses in its face and holes from each recess through the slat, and a rubber having substantially the same curve as the washboard and comprising slats, each having a series of recesses of the same shape in its face, 95 substantially as described.

In testimony whereof I affix my signature in presence of two witnesses.

MERRITT L. STODDARD.
